IMPACT-PULVERIZER.

1,212,991.

Specification of Letters Patent. Patented Jan. 16, 1917.

Application filed October 20, 1911. Serial No. 655,716.

To all whom it may concern:

Be it known that I, RAY C. NEWHOUSE, a citizen of the United States, residing at Milwaukee, in the county of Milwaukee and State of Wisconsin, have invented a certain new and useful Improvement in Impact-Pulverizers, of which the following is a specification.

This invention relates to improvements in the construction of rotary impact pulverizers in which raw material is pulverized by being repeatedly subjected to impact with a series of rapidly revolving beaters or bails.

The object of the invention is to provide a simple and efficient means for taking up the wear on the beaters or bails of impact pulverizers, such wear resulting from the grinding action of the material on the ends of the bails.

Another object of the invention is to provide a removable wearing shoe or bar adapted for attachment at the end of the bail, so that when the shoe or bar becomes worn it can be replaced by another without necessitating replacement of the entire bail.

A clear conception of several embodiments of the invention can be had by referring to the drawings accompanying and forming part of this specification, in which like reference characters designate the same or similar parts in the different views.

Figure 1 is a central vertical section through an impact pulverizer casing showing a series of beaters or bails with removable wearing shoes mounted thereon. Fig. 2 is an enlarged front view of one of the bails showing a removable wearing shoe or beater portion mounted thereon. Fig. 3 is a side view of a modified form of bail attached to a suspension member. Fig. 4 is a front view of a modified form of bail having a removable wearing bar or beater portion mounted thereon. Fig. 5 is a front view of a modified form of bail or beater portion constructed of one piece. Fig. 6 is a side view of a suspension member having the modified form of bail as disclosed in Fig. 5, pivoted thereon.

The impact pulverizer, see Fig. 1, consists essentially of a rotor and an inclosing casing comprising a lower portion or base 6, an inlet portion or hopper 1, and a cover 2. The pulverizer shaft 9 is mounted in end bearings formed in the casing and has a sus-

pension member 8 fixed thereto at a point 55 intermediate the shaft bearings. The beaters or bails 10, 11, 12, are suspended from a series of pivots 13, which are fixed to the suspension member 8. The liners 3, 4, 5, are fixed to the cover 2 of the casing and have 60 involute impact surfaces formed thereon, these surfaces being formed with the circular path of the end of the bails as an approximate generating surface. The screen bars 7 are mounted in the base 6 of the casing and permit the free discharge of pulverized material from within the pulverizing chamber.

The beaters or bails 10, 11, 12, see Figs. 1 and 2, are provided with removable beater portions or wearing shoes 14, these shoes being fixed to the ends of the bails by means of dovetails 15 coating in similarly formed recesses or slots in the ends of the bails. The dovetails 15 and the slots in which they coact, extend along the entire length of the shoes 14 and bails 10, 11, 12, the members being locked together by means of pins 16, which pass transversely through the said shoe and bail. The locking of the shoes to 80 the bails is insured by so inserting the pins 16 that one half of the pin extends above and the other half below the plane of coaction between the shoes and bails. The portions of the beaters or bails 12 not including 85 the wearing shoes are of considerably less length, measured radially of the rotor, than similar portions of the beaters or bails 11, while corresponding portions of the bails 11 are of considerably less length, measured 90 radially of the rotor, than corresponding portions of the bails 10. The overall radial lengths of the bails with the wearing shoes attached, are, however, the same, so that the radial distances from the centers of the suspension pivots 13 to the center of the shaft 9 are equal. It will thus be noted that since the lengths of the bails 10, 11, 12 are different, and the distances from the centers of the suspension pivots 13 to the center of 100 the shaft 9 are equal, the thickness of the wearing shoes 14 applied to the bails 12, 11, 10, respectively, must increase in order that the outer extremities of the shoes 14 do not extend beyond the circle of the screen bars 105 and liners.

In the modified form of bail disclosed in Figs. 3 and 4, the pivots 13 are equidistant.

from the shaft center. Each of the bails 100, 101, 102, comprises a pair of radially extending eye-bolts the outer ends of which have screw threads 150 which coact in screw threads formed in the removable beater portions or wearing bars 141. The loops of the eye-bolts are bored and adapted to receive the pivots 13. The bolts 102 are considerably shorter than the bolts 101, while the bolts 101 are considerably shorter than the bolts 100. In order that the overall lengths of the bails be the same, the bars 141 which are secured to the outer ends of the bolts 102 are considerably thicker, measured radially of the rotor, than the bars 141 secured to the outer ends of the bolts 101, while the bars secured to the bolts 101 are considerably thicker, measured radially of the rotor, than the bars which are secured to the ends of the bolts 100.

In the modified form of the invention disclosed in Figs. 5 and 6, beaters or bails 110, 130, 120 are formed with the wearing bars integral with the arms, the lengths of the bails, measured radially of the rotor, being different. The entire bail in this case forms the beater portion. The wearing bar 140 of the bail 110 is considerably thicker, measured radially, than the wearing bar 140 of the bail 130, while the wearing bar of the bail 130 is considerably thicker than the bar of the bail 120. In order to retain equal distances from the center shaft to the outer extremes of the bails, the distances from the centers of the pivots 13 to the shaft center are different. The bail 110 has its pivot nearer to the shaft center than the bail 130, while the bail 130 is mounted nearer to the shaft center than the bail 120.

During the operation of the pulverizer, the shaft 9 and suspension member 8 are given a rapid rotary motion carrying with them the beaters 10, 11, 12. The raw material to be pulverized is admitted through the inlet portion or hopper 1 of the casing and falls directly into the circular path of the moving bails. The rapid motion of the beater portions which traverse a circular path, causes the material to be thrown by the impact and by the action of centrifugal force, against the involute surfaces of the liners 3, 4, 5. The material after striking the involute liners is returned to the path of the beater portions, from which it is again thrown against the liners. The successive outward throwing and returning of the material from and to the beater portion path continues until the material is sufficiently pulverized to be drawn by suction from within the pulverizing chamber through the discharge screen. Due to the successive impacts of the beater portions 14 with the material, and also due to grinding of the material between the screen bar 7 and the ends of the bails, the beater portions

eventually become worn, causing the existence of a greater space between the ends of the bails and the screen bars 7. This increase in the width of the space between the ends of the bails and the screen bars causes the discharged product to become coarser, necessitating a means for outwardly adjusting the beater portions.

In the form of the invention disclosed in Figs. 1 and 2, the adjustment for wear is made by removing the worn shoe 14 from one of the bails and inserting the same in the next longer bail. For instance, as the shoe 14 of the bail 12 becomes worn, it is removed and inserted in the next longer bail 11, a new shoe 14 being inserted in the end of the bail 12. The shoe 14, removed from the bail 11, is inserted in the next longer bail 10, while the shoe 14, formerly attached to the bail 10 after having been worn, being unfit for further use, is discarded. In this way it will be seen that the shoes 14 can be completely utilized and that the parts subjected to wear can be easily replaced without renewal of the entire bails.

In the modified form of the invention disclosed in Figs. 3 and 4, the progress of the wearing bars 141 is similar to that of the wearing shoes 14 as disclosed in Figs. 1 and 2, the method of attaching and removing the bars 141, however, differing. The bars 141 are removed from their respective eye-bolts by removing the entire bail from its pivot and unscrewing the eye-bolts from the bar. With this construction it will be apparent that each of the suspension pivots 13 automatically and effectively locks the screw-threaded ends of the eye-bolts which form the means for securing the eye-bolts to the beater bar, against displacement since the pivot besides forming a means for swingably suspending the bail, also prevents relative rotation of the eye-bolts and the attached wearing shoe or beater portion. It will be noted that the bars 141 can be attached to pairs of eye-bolts 100, 101, 102, of suitable lengths, thereby again permitting complete utilization of the bars 141 and replacement thereof, without necessitating renewal of the eye-bolts.

In the modification of the invention as disclosed in Figs. 5 and 6, the bail 110 is advanced to a pivot which is mounted farther away from the shaft center, after its corresponding impact bar 140 has become worn, the bail 130 constituting the worn bail in its new position. After the bail 130 has become worn, it is advanced to a pivot having a still greater distance between its center and the center of the shaft, the bail 120 constituting the advanced bail in its new and final position. After the bail 120 has become further worn, it is unfit for further use.

With these constructions of bails it will

be seen that a simple and efficient means for maintaining the proper fineness of the discharged material is obtained. It will also be seen that the greatest amount of service possible is to be had from the bails. With the

5 construction as disclosed in Figs. 2 and 4, the beater portions 14, 141, can be made of any desirable material, as, for instance, tool steel, without necessitating the construction 10 of the bails 10 and bolts 101 of a similar material. The means of attaching the beater portions in each of these two constructions is also simple and efficient and permits ready removal of the beater portions.

15 By arranging the beaters of the several series so that diametrically opposite beaters are of substantially like thickness, the impact rotor may be maintained in a substantially balanced condition at all times. Such 20 balancing of the rotor is desirable due to the high rate of revolution thereof which is necessary in order to produce most efficient pulverization. If the rotor is not substantially balanced, undesirable vibration of the 25 machine results. The provision of several series of beaters of different thicknesses also permits gradual renewal of the worn out beaters, two at a time, without necessitating 30 simultaneous renewal of all of the beaters. If all of the beaters are renewed at the same time and allowed to remain in their initial position until they are completely worn out, there will be considerable difference 35 between the clearance at the ends of the beaters at the time of renewal thereof and the clearance existing just preceding discarding of the worn out beaters. This difference in clearance would produce considerable 40 difference in the fineness of the material discharged from the pulverizer at different times.

It should be understood that it is not desired to be limited to the exact details of construction shown and described, for obvious modifications will occur to a person skilled in the art.

It is claimed and desired to secure by Letters Patent,—

1. In combination, a rotary shaft, and a series of bail-shaped beaters suspended from said shaft, each of said beaters comprising a pair of spaced radial suspension arms and a cross-bar detachably secured to the outer ends of said arms and extending longitudinally of said shaft, and the bars of successive beaters being of different thicknesses.

2. In combination, a rotary element, a pair of arms each having a threaded end, a pivot for suspending said arms from said element, and a beater having threaded sockets engaging said threaded arm ends, said pivot serving to lock said arms against movement relative to said beater.

3. In combination, a rotor comprising a plurality of beaters of progressively different thickness, diametrically opposite beaters being of substantially like thickness.

4. In combination, a rotor comprising several series of beaters, each beater comprising a plurality of spaced suspension arms and a bar secured to said arms, the bars of successive beaters of each series being of different thickness, and diametrically opposite beaters of said rotor being of like thickness.

In testimony whereof, the signature of the inventor is affixed hereto in the presence of two witnesses.
